US0D1077690S

(12) **United States Design Patent** (10) **Patent No.:** **US D1,077,690 S**
(45) **Date of Patent:** **** Jun. 3, 2025**

(54) **ROLLING WALKER**

- (71) Applicant: **Zhejiang Medisite Medical Equipment Technology Co., Ltd.**, Hangzhou (CN)
- (72) Inventors: **Zhikuo Liu**, Hangzhou (CN); **Lijung Jiang**, Hangzhou (CN); **Zhixiang Fan**, Hangzhou (CN)
- (73) Assignee: **Zhejiang Medisite Medical Equipment Technology Co., Ltd.**, Hangzhou (CN)
- (**) Term: **15 Years**
- (21) Appl. No.: **29/908,815**
- (22) Filed: **Jan. 16, 2024**

Related U.S. Application Data

- (63) Continuation-in-part of application No. 29/909,927, filed on Aug. 12, 2023, which is a continuation-in-part of application No. 29/879,806, filed on Jul. 12, 2023.
